SHOULDER MARK

Solomon Mars, New York, N. Y.

Application August 18, 1944, Serial No. 550,089

4 Claims. (Cl. 2—246)

1

This invention relates to new and useful improvements in shoulder marks.

More particularly, the invention proposes a new and improved shoulder mark which is intended to be worn with service or other uniforms.

Heretofore it was customary to provide a rigid shoulder board in a cloth casing. A flexible strip for attaching the cloth casing and shoulder board to a uniform, in accordance with the old construction, was attached to the cloth casing. This arrangement embodies numerous defects. In a short period of time the cloth casing would lose its body and then the shoulder strap would be loosened. Later on, the cloth casing would tear, so that the strap would tear away.

This invention proposes a shoulder mark which is characterized by the fact that the flexible strap is rigidly connected with the rigid shoulder board. The cloth casing is provided with a slit through which the rear end of the flexible strap extends so that it may be secured to the rigid shoulder board.

The invention also contemplates modified forms, one of which is disclosed and is characterized by an arrangement by which the flexible shoulder strap may be disconnected from, and connected with, the shoulder board at will.

Still further, the invention proposes a shoulder mark which is simple in construction, durable, and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a shoulder mark constructed in accordance with this invention.

Fig. 2 is a longitudinal sectional view of the shoulder mark shown in Fig. 1.

Fig. 3 is a bottom view of the shoulder mark shown in Fig. 1.

Fig. 4 is a fragmentary bottom view of a shoulder mark constructed in accordance with a modified form of this invention.

Fig. 5 is a fragmentary sectional view taken on the line 5—5 of Fig. 4.

The new and improved shoulder mark, in accordance with that form of the invention disclosed in Figs. 1 to 3 inclusive, includes a rigid shoulder board 10 preferably constructed of thermosetting composition material. The board

2

10 is of ornamental design and has one end formed with a point. This is a standard design for one type of shoulder mark. A cloth casing 11 engages about the shoulder board 10. This cloth is shown constructed of two pieces, a top piece 12 and a bottom piece 13, which are secured together by lines of stitches along their edges.

A flexible strip 14 preferably of relatively thick leather, or some similar flexible material, passes through a slit 15 formed in the bottom layer 13 of the cloth casing 11. The inner end of the flexible strip 14 is secured to the shoulder board 10 by several fastening elements such as studs 16.

The outer ends of the flexible strip 14 and the covered shoulder board 10 are formed with the usual eyelets 10^a and 14^a at the outer ends of the board and strap respectively, which parts 10^a and 14^a provide a means at the outer end of the mark for engagement with any flexible or other tie-down means, as the familiar tape loops on the shoulders of naval uniforms.

The use of this shoulder mark is identical to similar prior articles. However, the main feature of the invention resides in the fact that the flexible strip 14 is attached to the rigid shoulder board 10.

In Figs. 4 and 5, a modified form is shown. In this form of the invention, the shoulder board 10 is formed with a group of bayonet slots 18. The inner end of the flexible strip 14 is provided with headed studs 19 which were engaged through the large ends of the bayonet slots 18 and which then were moved to the small ends of the bayonet slots so as to rigidly connect the flexible strip 14 with the shoulder board 10. The slit 15 in the cloth casing 11 through which the flexible strip 14 passes is just wide enough for the flexible strip 14 to pass. For this reason the cloth casing 11 will hold the flexible strip 14 in the position illustrated on the drawing, in which position the headed studs 19 are in the small ends of the bayonet slots 18.

When it is desired to remove the flexible strip 14 it is necessary that the inner end of the flexible strip 14 be moved laterally against the relatively weak holding action of the cloth casing 11. The cloth casing 11 may shift slightly about the rigid board 10 or may flex or be stretched. When the headed studs 19 are in the large ends of the bayonet slots 18, the inner end of the flexible strip 14 will be lifted so as to disengage the headed studs from the bayonet slots. The strip 14 is now free to be removed.

While I have illustrated and described the preferred embodiments of my invention, it is to be

understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A shoulder mark, comprising a rigid shoulder board, a cloth casing for said shoulder board, a flexible strap attached to said shoulder board and extending out of a slit in said casing, and headed studs cooperative with bayonet slots for releasably attaching said flexible strip with said shoulder board.

2. A shoulder mark, comprising a rigid shoulder board, a cloth casing for said shoulder board, a flexible strap attached to said shoulder board and extending out of a slit in said casing, and headed studs cooperative with bayonet slots for releasably attaching said flexible strip with said shoulder board, and said slit being of a width to engage the edges of said flexible strap for holding the flexible strap so that the headed studs remain engaged in said slots.

3. A shoulder mark having a rigid shoulder board enclosed within a cloth casing, a flexible strap extending along the bottom face of said shoulder board and having one end extended into said casing through a slit to a position adjacent the bottom face of said shoulder board, and means

securing the inner end of said flexible strap to the bottom face of said board, comprising headed studs on said flexible strap releasably engageable with complementary bayonet slots formed in said shoulder board.

4. A shoulder mark having a rigid shoulder board and a fabric casing enclosing the same, said casing having a slit therein disposed across one end of the shoulder board and adjacent to the bottom face of the shoulder board, said shoulder board being provided with a plurality of slots disposed in a row parallel to the slit, and each of said slots having a wide and a narrow end, a flexible strap disposed under and against the bottom face of the shoulder board and having one end thereof extended through said slit into said casing, and studs carried by said end engageable with the slots of the shoulder board to detachably couple said flexible strap to the shoulder board, the board and strap having openings in their outer end to receive a tie.

SOLOMON MARS.
